BY Geo. J. Haight

ATTORNEY.

UNITED STATES PATENT OFFICE.

GEORGE A. JOHNSON, OF CHICAGO, ILLINOIS, ASSIGNOR TO WILLIAM H. MINER, OF CHAZY, NEW YORK.

SIDE BEARING FOR RAILWAY-CARS.

1,281,386.

Specification of Letters Patent. Patented Oct. 15, 1918.

Application filed March 23, 1917. Serial No. 156,878.

To all whom it may concern:

Be it known that I, GEORGE A. JOHNSON, a citizen of the United States, residing at Chicago, in the county of Cook and State of

5 Illinois, have invented a certain new and useful Improvement in Side Bearings for Railway-Cars, of which the following is a full, clear, concise, and exact description, reference being had to the accompanying 10 drawings, forming a part of this specification.

My invention relates to improvements in side bearings for railway cars.

The object of my invention is to provide 15 a simple side bearing of the rocker type in which provision is made for the lateral adjustment of the rocker.

In the drawings forming a part of this specification, Figure 1 is a longitudinal vertical section through a side bearing embodying my invention. Fig. 2 is a cross section taken on line 2—2 of Fig. 1. Fig. 3 is an 20 end view of the rocker.

Referring to the drawings, the numeral 10 25 indicates a base member provided with suitable means, as, for instance, the flanges 11—11 and the rivets 12—12 to secure it to the bolster of a car, as, for instance, the truck bolster 13. The base member 10 is 30 provided with an upwardly opening hollow interior 14 in which is mounted the rocker 15. The tread 16 of the base member is curved laterally as indicated at the numeral 17, the rocker 15 upon its lower face being 35 similarly curved as indicated at the numeral 18. In its under face the rocker is provided with the apertures 19—19 adapted for the entrance of the spacing lugs 20—20 which are preferably integral with the base 40 member. The rocker is longitudinally provided with a perforation 21 adapted to receive the pin 22, which is of smaller diameter than the opening 21 and extends at its ends 23—23 into the lateral internal 45 grooves 24—24 longitudinally arranged in the base member 10. The base member is perforated at a point registering with one of the grooves as indicated by the numeral 25 to permit the passage of the pin 22 into 50 its position after the rocker has been inserted in the base member. The accidental displacement of said pin through said opening is prevented by suitable means, as, for instance, the cotter 26. On the opposite side 55 of the base member a perforation 27 is pro-

vided to permit the driving out of the pin 22 when desired. The grooves 24—24 are of a greater height than the diameter of the pin 22.

It will be observed that when the bearing 60 plate upon the opposed bolster, as indicated at 28, engages the rocker angularly, that is, when there is an angularity between the plane of the bottom of the base member and the bearing plate upon the opposed bolster, 65 the rocker will adjust itself laterally upon the curved tread 17 in the base member, and this adjustment will permit the full bearing of the upper face 29 of the rocker from side to side thereof against the opposed bearing 70 plate 28. The looseness of the pin 22 within the rocker and at its ends within the grooves 24 will permit the aforesaid lateral adjustment of the rocker and at the same time the pin will prevent the accidental displacement 75 of the rocker from its position within the base member. The grooves 24 are sufficiently extended longitudinally to permit the travel of the pin with the rocker in either 80 direction.

I claim:

1. In a side bearing for railway cars, in combination: a retaining member; a rocker mounted therein; said retaining member having a curved tread, and the rocker being 85 similarly curved to engage said tread to permit lateral oscillation of the rocker within the base member and about an axis perpendicular to the line of rocking movement.

2. In a side bearing for railway cars, in combination: a retaining member; a rocker mounted therein; a pin extended at its ends from said rocker; the retaining member and rocker having engaging transversely curved bearing surfaces, the retaining member being provided with longitudinal grooves, the ends of the pins extending into said grooves and having both longitudinal and vertical 95 movement therein.

3. In a side bearing for railway cars, in 100 combination: a retaining member; a rocker mounted therein; a pin; a perforation through the rocker to receive said pin; the rocker being laterally oscillatable upon said pin, the retaining member and rocker being 105 provided with engaging curved bearing surfaces.

4. In a side bearing for railway cars, a retaining member, a rocker mounted therein, a pin extended through the rocker, the 110

retaining member and rocker being provided with engaging transversely curved bearing surfaces, the said base member having longitudinal grooves for receiving the 5 ends of the pin, the pin being loosely received in said grooves and in said rocker, all to permit the lateral oscillation of the

said rocker in reference to the retaining member.

In witness that I claim the foregoing I 10 have hereunto subscribed my name this 20th day of Mar., 1917.

GEORGE A. JOHNSON.
